Primary Examiner — Caron D Veynar*Assistant Examiner* — Katelin G Kloberg(74) *Attorney, Agent, or Firm* — Carlson, Gaskey & Olds P.C.(57) **CLAIM**

The ornamental design for a bead tray, as shown and described.

DESCRIPTION

FIG. 1 is a top, right, front perspective view of a bead tray, showing my new design;

FIG. 2 is a top plan view thereof;

FIG. 3 is a right side elevational thereof;

FIG. 4 is a left side elevational view thereof;

FIG. 5 is a rear elevational view thereof;

FIG. 6 is a front elevational view thereof; and,

FIG. 7 is a bottom plan view thereof.

The broken lines illustrate portions of the bead tray that form no part of the claimed design.

1 Claim, 5 Drawing Sheets(56)
